UNITED STATES PATENT OFFICE.

CHARLES G. BROSTROM, OF LYNN, AND ANDREW R. RIDDERSTROM, OF NAHANT, MASSACHUSETTS, ASSIGNORS TO BEACON FOLDING MACHINE COMPANY, OF LYNN, MASSACHUSETTS, A CORPORATION OF MASSACHUSETTS.

FOLDING MACHINE.

Application filed November 12, 1917, Serial No. 201,564. Renewed November 5, 1924.

To all whom it may concern:

Be it known that we, CHARLES G. BROSTROM and ANDREW R. RIDDERSTROM, citizens of the United States, and residents, respectively, of Lynn, in the county of Essex and Commonwealth of Massachusetts, and of Nahant, in the county of Essex and Commonwealth of Massachusetts, have invented an Improvement in Folding Machines, of which the following description, in connection with the accompanying drawings, is a specification, like characters on the drawings representing like parts in each of the several views.

This invention relates to power operated automatic folding machines of a type that while having other and more general fields of usefulness is especially adapted and designed for folding down the edges of shoe vamps according to the common present day practice in shoe manufacture. One principal object of the invention is to provide an improved machine of this type capable of relatively short feed strokes as compared with previously known types of machines for folding. Another important object of the present invention is to provide a vibrating folding hammer having a lateral extension presenting a diagonal folding edge extending generally in the direction of the fold, this hammer folding edge thus reaching up closer to the folding point, i. e., to the edge of the plow and to a relatively longer extent engaging the stock. A further object is to provide a folding hammer equipped with a retainer or presser finger adapted to engage the stock as the hammer descends some little distance outward therefrom, this preventing turning of the stock when the hammer is down and insuring the turning of the stock about the retainer in running curves. In accordance with our invention this retainer-member is yieldably and also adjustably mounted so that it may be swung upward or downward so as to bring it against the work with the degree of pressure required. A further important object of the invention is to provide a movable plow or abutment for folding or turning the stock, mounted for a small yielding backward movement so that seams or the like in the work are the more readily cleared and also so that the plow may have a minute

vibrating or wiggle movement whereby it takes a new hold against the stock at each feed movement and prevents bunching or uneven puckering of the folded edge. Another important object is to provide an improved construction and arrangement of the control connections for the operating parts whereby the snipping knife may be controlled as to its operative position by the same treadle which controls the feed point, and preferably so that, by a single continuing movement of such treadle, the feed point is first rendered operative and then by a further movement, the snipping knife is moved into operative position variably to the required extent. A further object is to provide an improved construction of feed point equipped with a retainer finger adapted to hold back the stock from turning prematurely. A further object is to provide, in combination, a hammer block and co-operative hammer face sloping upward outwardly, thus lessening the strain on the upper edge of the fold and contributing to a longer folding edge as well as being especially useful in turning sharp corners. A further object is to provide an improved co-operative arrangement between the folding hammer and the feed point, whereby the hammer is held down to grip the work during the interval that it is released by the feeding point and as the feed point moves backward. A still further object is to provide means permitting a fine adjustment of the upper feed point endwise thereof with reference to the plow so that it may be properly positioned with respect thereto for its work. A still further object is to provide an improved mounting and arrangement of the snipping knife, wherein such knife is normally spring-held outward, and capable of being drawn invariably to operative position by a treadle movement which is preferably the same treadle movement that controls the feed point. The foregoing and other objects and advantages of the invention will more fully appear from the following detailed description, and the distinctive features of novelty will be pointed out in the appended claims.

40 Fig. 16 is a similar, partial, sectional view, on the same section line, showing the parts as they appear in the operation of snipping;

Fig. 17 is a partial, plan view, illustrating the operation of the operating elements on a piece of stock;

45 Fig. 18 is an enlarged plan view, partly in section, of the feeding and folding instrumentalities as they appear at the commencement of the feeding movement;

50 Fig. 19 is a similar view, showing the parts in the positions assumed after the feed elements have advanced about half the distance of the feeding movement;

Fig. 20 is a similar view, with the parts in the positions occupied at the end of the feeding movement;

55 Fig. 21 is a similar view, with the feed elements shown as having retraced half the distance to the starting point; and

60 Figs. 22 to 25 inclusive are front elevations, partly in section, corresponding, respectively, to Figs. 18 to 21 inclusive.

The frame-work or housing 10 of the machine comprises a base portion 10^a, with an operating head or horn 10^b projecting horizontally forward therefrom and with a low, curved, overhanging portion 10^c ex-

tending forward over the horn 10^b and spaced therefrom. The prime, drive shaft of the machine is indicated at 11, this being horizontally journaled in the housing in substantially the plane of the feed elements, referred to below, with its outer portion having bearing through a hub 12 of the frame housing and an outer projection of this shaft having a clutch wheel 13 keyed thereon.

Loosely fitted on the shaft 11, without the 70 clutch wheel 13, is a usual cone pulley 14, having a clutch face at its inner side co-operative with an outer clutch face of the wheel 13, these clutch faces being normally held apart by a coil spring 15 pressing the 80 pulley 14 outward against a shoulder 16 formed on a bearing collar 17, slidably fitted on the outer extremity of the shaft 11. The collar 17 has fixed, in its outer end, a

wear button 8, engageable by a wear piece 85 19, carried on the upper end of a curved lever arm 20, which is journaled to the frame at 21 and has an inward extension 22,

pivotaly connected at 23 with a treadle rod 24 extending downward and slidably guided 90 in a lug 25 of the frame. A spring 26, re-

acting against this lug, normally holds the lever arm 20 swung outward or, at least, neutralizes the treadle weight, so that said 95 arm does not press the clutch faces into en-

gagement. A depending lug 27, rigid with the arm 20, is equipped with a striker bolt 28, which is adapted to engage a depending 100 tail 29 of a brake member 30, which is pivoted to the fulcrum member 21 and adapted to press against the inner side of the wheel 13.

Thus, as the treadle rod 24 is depressed, the clutch faces of the pulley 14 and the wheel 13 are brought into operative en-

gagement, while upon the release of the 105 treadle, the spring 15 separates these clutch members and the spring 26, lifting the lever arm 22, will cause the striker bolt 28 to act on the brake 30 to stop the machine.

The inner end of the shaft 11 has bearing in a 110 journal block 31, fixed to a pin 32 secured cross-wise in the frame housing. In order

that the feed elements may be operated at high speed, they are positively connected to their operating instrumentalities by a mecha-

nism now to be described. The inner extremity of the shaft 11 is equipped with a crank pin 33, to which is fitted a ball 34,

fitting in a socket 35 at the inner end of an arm 36, which constitutes a holder for the 115 upper feed point, as now to be described.

This feed point, indicated at 37, has an inwardly extending shank portion 37' which is held down to the arm 36 by a clamp member 38. The under side of this shank por-

tion is serrated for a distance, as seen at 39, for engagement by a toothed pinion 40, transversely journaled at the rear of the arm 36. The pinion 40 is adapted to be rotatably 120 adjusted and clamped in adjusted position

125

120

125

120

for setting the feed point in correct and accurate endwise adjustment across the lower feed block and the other operating parts to adjust the path of feed movement.

5 The arm 36 is pivoted to swing vertically on an intermediate pivot pin 41, secured transversely to ears extending inwardly from a bracket plate 42, pivoted to a pin 43, secured to a block arm 44, so that the plate 42 is 10 permitted to swing or rock horizontally, sliding on the upper face of the block 44. The block arm 44, in turn, is hinged to a transverse pivot 45 at the front of the horn 10°. The arm 44 extends inwardly some 15 little distance beyond the pivot 41, having pivoted at its inner extremity, as seen at 46, two depending link bars 47, 48 for controlling the vertical swinging movement thereof, as presently to be explained. The outer 20 extremity of the plate 42 has secured thereto the lower feed block 49, in position to act opposite the outer down-turned extremity 50 of the upper feed point. It may now be understood that the orbital movement of the 25 crank pin 33 operates to swing the arm 36, with the upper feed point, vertically about the pivot 41, and, at the same time, to swing the bracket plate 42, bearing the lower feed block, as well as the upper feed point, horizontally about the pivot 43, such horizontal swinging producing the feed movement, and the vertical swinging of the upper feed point alternately gripping and releasing the work, as required. It will further be understood 30 that, as the arm 44 is swung upwardly on the pivot 45, since the lower feed block 49 is outward of such pivot, it will be depressed, while, at the same time, the upper feed point, with the arm 36, then swinging about the ball 34 as the fulcrum, will be raised, so 35 that the material to be operated on may be inserted; while, by swinging the arm 44 downward, the lower feed block 49 is swung upward and the upper feed point 50 is 40 simultaneously swung downward, so as to approach the lower feed block in its orbital movement, it being understood that these 45 opening and closing movements may be carried out without disturbing the continued 50 operation of the material feeding movements, as imparted by the crank pin 33. For drawing the arm 44 normally downward, i. e., so as to render the feeding elements normally effective, a compression coil 55 spring 51 is provided, this being fitted on a reduced depending extension 52 of the bar 48, which is slidably guided through a collar 53, fixed on a pin 54, set into the frame work. The spring 51 reacts against an adjustable nut 55 threaded on the lower end of 60 the rod extension 52, and thus tends to draw the same downward, as far as permitted by an adjustable stop nut 56, threaded on said rod portion above the bearing collar 53 and 65 adapted to abut thereagainst to limit the downward swing of the arm 44. Thus, by adjusting this nut 56, the degree to which the feed point 50 and the feed block 49 will approach each other, in operation, can be adjustably limited, as required for different 70 thicknesses of stock, or other reasons, and the force of the bite with which the feed point engages the stock may be regulated by adjusting the nut 55, so as to vary the tension of the spring 51, as required. For 75 swinging the arm 44 upward, to separate the feed point and the feed block, to release the material and for inserting the same, a lower forked end 57 of the bar 47 is engaged by a pin 58, carried by a lever arm 59, pivoted on 80 the pin 54 and having its outer end engaged with a treadle rod 60, this, of course, typifying any suitable manual, or other controlling means. The lever arm 59 is acted on by a compression, coil spring 61, bearing 85 against an abutment 62 of the frame to hold the same and the treadle normally lifted. The spring 61 normally opposes the spring 51, thus maintaining the feed elements normally ineffective. In accordance with the 90 present invention, the snipping knife, which snips the stock at intervals in running curves, is connected to be controlled, for progressively varying the depth of the 95 snip cuts by the same treadle or like controlling means that controls the feeding elements. For this purpose, the lever arm 59 has rigid therewith an upright angular extension 63, formed with a socket 64, into which extends the outer end of a knife-controlling rod 65, the end of this rod being engaged by an adjustable pin abutment 66, threaded into the arm extension 63. Another extension downward from the inner 100 end of the arm 59, as seen at 67, is equipped with an adjustable stop pin 68 to limit the upward swing of said arm. The knife-controlling rod 65 has its inner end pivotally connected, at 69, to a lever 70, pivoted at an intermediate point to the frame, as 105 seen at 71, and having its upper end pivotally connected at 72 with a link bar 73, which is connected at its outer end with the pivot pin 74, on which is mounted a bent 110 lever 75, having fixed at its outer end the movable, snipping knife 76. Co-operative with this movable snipping knife, for snipping the material, is a fixed knife block 77, just within the lower feed block. The pivot pin 74 is also connected with a lever 115 arm 78, which is pivoted to the frame at 79 and has opposite, lateral extensions 80, 81, engageable by adjustable stop pins 82, 83, set into the frame housing. These stop pins are adjusted so as to allow the requisite 120 range of swinging to the arm 78, as required for adjusting the pivot 74, to vary the depth of the snip cuts to the extent required. In practice, the stop 82 may be 125 permanently set, so that when the arm 80 is 130

pressed thereagainst, the snipping knife is just out of operative position, in which position it is normally held by a tension coil spring 84, anchored to the frame and engaged with the bar 73, as seen at 85. The other stop pin 83 may be adjusted as required to vary the maximum depth of the snip cuts obtainable and to facilitate such adjustment, it may be equipped with a knurled head and lock nut, as seen at 86. With this mounting of the knife-holding arm 75, it will be noted that the snipping knife 76 is normally held out of effective position by the spring 84 and may be pressed into operative position, to the extent required, by the treadle movement, as imparted through the rod 65. In practice, the outer end of the rod 65 is normally spaced a small distance from the end of the adjustable pin abutment 66, so that the treadle movement does not start to move the snipping knife into operative position until after the treadle has been depressed far enough so that the pin 58 has receded sufficiently to permit the spring 51 to move the feed elements into effective relation. In this way, a downward movement of the treadle element 60 first throws the feed members 49, 50 into effective relation and then a continuance of the same treadle movement gradually moves the snipping knife 76 into effective position, such knife being moved in farther as the treadle is further depressed, to vary the depth of the snip cuts, as required; this, it will be observed, does not affect the operation of the feeding elements, since the arm 44 is only permitted to swing down as far as the adjustment of the nut 56 allows. For operating the snipping knife 76, the arm 75 has its outer end pivotally connected, as seen at 87, with a pitman rod 88, whose other end is connected to a crank pin 89 on a spiral gear 90, journaled at 91 in the machine housing. The spiral gear 90 is driven by the co-operative spiral gear 92, fixed on the drive shaft 11. In practice, it is found not necessary that a snip cut be made at each feed movement but that such cut, at alternate feed movements, is ample and accordingly the spiral gear 90 is made twice the size of the gear 92, these gears being both of the 45° pitch usual in spiral gears, this resulting in an actuation of the knife 76 at every other feed movement as imparted by the crank pin 83. In our copending application, Serial No. 168465, filed May 12, 1917, we have disclosed a folding machine the feed block of which is integrally provided with a plow that is adapted to form an initial fold in the stock during the return movement of the feed elements. The plow then moves forward with the feed elements during their next forward feed movement to advance the initially formed

fold to the hammer, by which the fold is pressed down. An important feature of our present invention has to do with a plow or folding abutment member mounted upon the feed block not integrally, but movably for small yielding by the pressure of the material thereagainst, so as to permit a more free clearance of seams or other thick places in the stock and also so as to insure a more even folding without bunching or puckering of the stock. The terms "folder" and "plow" will hereinafter be employed interchangeably. The folder or plow is indicated at 93 and comprises an upright prong with a suitably formed folding face. It is pivoted to a vertical pivot 94 on a forward projection 95 of the swinging plate 42, which carries the lower feed block 49. The front, operative face 96 of the plow is normally held pressed up to the back of the feed block by a compression coil spring 97, re-acting against an arm 98, rigid with, and projecting forwardly from, the plow, this spring having backing against an adjustable abutment 99 in the machine frame. It has been found highly desirable for the purpose of insuring an even smooth fold without bunching or puckering of the stock that the plow be vibrated or wiggled slightly, so as to take a new hold against the work at each feed movement. To bring this about, we provide an adjustable abutment member in the form of a threaded pin 100, set into the machine frame and adapted to be set up so that its inner end will engage against the arm 98 upon the return feed movement, to positively swing the plow backward slightly against pressure of the spring 97, thus insuring slight oscillation to the plow at each feed movement. The use of spring-operated, high-speed elements in a high-speed machine is, of course, objectionable, as such elements tend to lag behind the more positively controlled elements, with the result that the elements do not operate in synchronism. The plow, however, though spring controlled, is not spring operated. The spring 97 maintains the arm 98 always in engagement with the pin 100 except when the arm is forced out of engagement therewith by material of unusual thickness, as at seams, or for other such causes. The plow is positively actuated by the same mechanism that actuates the feed elements, but it is caused to pivot or wiggle with respect thereto by the constantly exerted action of the spring 97. The operation will be better understood from a consideration of Figs. 18 to 25. In Figs. 18 and 22, the feed elements are shown in their initial positions, at the commencement of the feeding movement. The feed point 50 has just returned in the direction of the lower, right-hand arrow, Fig. 18, and has closed in upon the material M, clamp-

ing it to the feed block 49. The spring 97 has been compressed in the direction of the left-hand arrow by the pin 100 engaging the arm 98 of the plow. The material M may be 5 leather, cloth, etc., or it may be composed of several elements, as where it is desired to fold a binding strip sewed to the edge of a strip of leather or cloth. With the parts so positioned, the feed elements and the plow 10 are about to advance forwardly, in the direction of the upper, right-hand arrow, Fig. 18, to feed the material M. During this forward movement, the edge of the material is maintained folded, as shown at F, the fold 15 having been initially turned up by the face 96 of the plow 93 during the rearward movement of the plow, as illustrated in Fig. 21. In this respect, the operation of the plow is somewhat similar to the operation of 20 the plow of our above-mentioned application. As the plow advances forwardly, the spring 97, acting to maintain the arm 98 in engagement with the pin 100, will cause the plow to pivot about the vertical pivot 94, 25 resulting in the above-described vibratory or wiggle movement. This vibratory movement results in the fold F becoming more pronounced, as will be made evident from a comparison of Figs. 18 and 19, the plow 30 finally closing in upon the feed point, as shown in Fig. 20, to fold the material still further and to effect a new hold or grip thereon.

The provision of a plow which folds during the forward movement thereof and which grips the material anew at each forward movement is a distinct advance over the structure of our above-identified application and is considered to be an important 40 feature of the present invention. A better control over the point or the line of fold is thereby obtained. Though the plow of our former application produced an initial fold in the edge of the material, there was 45 no way of determining the point at which the fold would be pressed down by the hammer. According to the present invention, the initial fold that is formed during the return movement of the plow, as shown 50 in Fig. 21, is later further developed during the forward movement thereof, and the developed fold is firmly gripped between the side of feed point and the plow; so that the point of fold is absolutely predetermined, 55 as shown more particularly at P in Fig. 24. The hammer will therefore press down the fold at exactly this point P and not at some other point to the right or to the left 60 thereof. The plow and the hammer thus cooperate to produce a more uniform edge fold than has hitherto been obtainable. If desired, the plow may grip the material not only at the lower portion of the fold, as shown, but at the upper or edge portion 65 65 also, the plow and the feed point cooperat-

ing both to grip the material and to fold it. In the present construction, the upper portion of the fold is not gripped, but is slightly bent over beyond the point P by the prong of the plow.

By the time that the edge has become folded and gripped as above described, and as shown in Figs. 20 and 24, the feeding instrumentalities have advanced the fold to the hammer. The hammer for pressing down the fold is indicated at 101 held from movement in the line of feed, and pivoted to the frame work at 102, this being an extension of the pivot bolt 45, and having an operative face 103 sloping upwardly outward and co-operative with a hammer block 104 set into the frame work and having a correspondingly sloped face. The outer edge of the lower feed block 49 which lies adjacent to this anvil face 104 is also raised 70 as seen at 105, this lessening the strain on the upper edge of the fold and contributing to a longer folding edge, and being a feature especially advantageous in turning sharp corners. In accordance with our invention, the hammer is also equipped with a lateral projection extending in back of the lower feed block, equipped with a diagonal edge 106 lying close to correspondingly cut away edges of the feed block and the feed point, this presenting a relatively elongated folding edge extending diagonally in the general direction of the fold, instead of straight across, the same as has heretofore 75 been usual. In this way, it will be noted that the hammer edge presses up closer to the folding point which, it will be understood, is highly important for the most successful and effective work. The hammer is 80 also equipped with a retainer member consisting in a finger 107, extending out in front of the hammer in the direction from which the stock is fed, this retainer finger being yieldably mounted and serving to prevent the hammer pushing the stock outwardly while pressing a fold and to hold the stock clamped firmly when the hammer is down at some little distance outward therefrom, so that it is not possible for the operative 85 to turn the stock about the hammer when it is down. This retainer finger is carried by and extends laterally from an arm 108, pivoted to one side of the hammer, as seen at 109, and yieldingly pressed so as to hold the retainer finger normally at a downward 90 limit of movement by a compression coil spring 110, reacting against an abutment on the hammer. The retainer finger itself is 95 preferably mounted for swinging adjustment on the end of the bent arm 108 and for this purpose, it has a toothed hub 111, extending into a socket in a head 112 at the end of the arm 108, this toothed hub being gauged so as to be turned by a 100 threaded stud 113 having a projecting 105 110 115 120 125 130

handle 114. A clamping screw 115 is set into the end of this stud to clamp the same in adjusted position by pressing against the face of the head 112, which is preferably split, as seen at 116, to provide the requisite spring clamping action. The hammer 101 is positively connected to its operating instrumentalities, so that it may be operated at high speed in timed relation to the operation of the feed elements. For vibrating the hammer 101, it is provided with an arm 101', depending below its fulcrum, which is pivotally connected to a collar 117, slidably mounted on a rod 118. The rod 118 has adjustably clamped thereto a fixed collar 119 which serves as an abutment upon the movement of the rod to the left, as shown, for raising the hammer. The outer end of the rod 118 has threaded thereon a nut 120, having a knurled head 121, this nut serving as an abutment for a stout compression coil spring 122, which presses against the outer end of the slideable collar 117, holding it normally against the fixed collar 119. Thus, as the rod 118 is reciprocated, the hammer will be swung downward for cushioned hammer strokes, by the pull of the rod, transmitted through the stout spring 122, whose tension may be adjusted, as required, by proper setting of the nut 120, while the hammer will be lifted by the engagement of the fixed collar 119 with the other end of the sliding collar 117. The spring 122 serves merely to maintain the collar 117 ordinarily in engagement with the fixed collar 119 and to permit the hammer to yield when stock of greater than ordinary thickness is encountered. The spring does not in any sense actually actuate or vibrate the hammer. For imparting the requisite, short amplitude reciprocations or vibrations to the rod 118 its inner end has fixed thereto a lateral upstanding bracket 123, the extremity of which is pivoted at 124 to the outer end of an arm 125, pivoted to the frame at 126. The arm 125 has fitted to slide lengthwise therein a bar 127, to which is pivoted, at 128, an extension of an eccentric strap 129, engaged with an eccentric 130, fixed on the drive shaft 11, the purpose of the sliding bar 127 being to permit operative pivotal connection of such eccentric strap which, of course, cannot move endwise of the arm 125, with such arm. The hammer is thus positively connected to its actuating mechanism. The connection of the lever arm 125 to the eccentric strap 129 is so arranged that the pivot 124 rises some little distance above a line projected from the pivot of the collar 117 through the pivot 126, this being to permit the requisite dwell of the hammer when clamping the work to hold it while the feeding elements are moving on their backward stroke, it being observed that the hammer will thus

get a double pinch on the material as the arm 125 shifts the pivot 124 past the dead center position in each direction. It will be understood, however, that the major portion of the swing of the pivot 124 is below 70 the center line mentioned, this being operative to lift the hammer. The upper, movable feed point 50 extends laterally over the lower feed block 49 some little distance, as best shown in Figs. 14-17, and its extremity is formed with an inturned retainer finger 131 adapted to engage the edge of the stock just in advance of the plow and hold it back from turning prematurely. 75

During the forward movement of the feed elements, the hammer and the retainer carried thereby are raised, as shown more particularly in Fig. 23. The hammer and the retainer, as shown in this view, have reached the limit of their upward movement, indicated by the upper arrow, and are on the point of commencing their movement downward, in the direction of the lower arrow. By the time that the forward feed movement has been completed, the retainer has 90 commenced to grip the material M, Fig. 24, and the hammer continues its downward movement to press out the fold prepared previously by the plow. The diagonal edge 106 of the hammer will first pinch the fold 95 at the point predetermined by the gripping action of the plow and the feed point, the latter advancing the material to the end of the diagonal pinching edge. The edge will remain in pinched position by cement 100 or otherwise while the material is further advanced by the next feed movement, the remaining portion of the hammer then pressing out the complete fold. Meantime, the feed elements have commenced to retrace their movement to return towards the starting position of Figs. 18 and 22. When the feed elements have released the material, therefore, the hammer presses down thereon and when the hammer has become raised 110 to release the work, the feed elements have again secured their grip thereon. It is impossible to turn the material either when the hammer is down or the feed elements are active. Just before the feed elements have 115 completely returned to their starting positions, however, before they have again gripped the material, and after the hammer has become raised from the work, the retainer still clamps down upon the work, but 120 lightly, as indicated in Fig. 22. At this time, the work may be turned in its plane about the retainer as a pivot. A moment later, the retainer becomes raised, but the feed elements resecure their grip upon the 125 work, making turning impossible until after another cycle of operations has become completed.

The retainer serves thus both to prevent the material being pushed outwardly away 130

from the hammer and to determine the point about which the material may be turned in its plane.

The forwardly extending horn 10^b has its top equipped with a platform 132, this presenting a horizontal surface at the working level over which the material is fed. This platform is a relatively small affair and is surrounded by a table 133 which may 10 be mounted from rearwardly extending arms 134 pivoted to the sides of the housing at 135 at a point relatively far back, these arms and the sides of the table straddling the platform and the upper part of the 15 housing so that the table may be swung up back over the housing, when desired. It will be understood that when swung downward, the forward portion of the table may rest on suitable adjustable abutments of the 20 housing. The operation of the machine will be readily understood from the foregoing without further detail statement. The material *m* whose edge *E* is to be folded is inserted when the feed point and the feed 25 block are separated, whereupon, on depressing the treadle rod 60 the feed point and the feed block are first brought to operative position starting the feed of the material *m* whose edges *E* is to be folded is 30 the hammer 101 are co-ordinated with the movements of the feed elements so that the hammer is down and holds the material clamped while the feed elements are moving on their backward stroke carrying the movable plow 93 with them for its operative 35 stroke, the hammer being then lifted as the feed movement takes place. On coming to a curved portion of the material, the operator depresses the treadle rod 60 farther, 40 which brings the snipping knife 76 into effective position to a variable extent, according to the depth of the snips required, this being determined by the degree to which the treadle rod is depressed. It will 45 be understood that the effective position of the feed point 50 is entirely under the adjustable control of the nut 56 when the treadle rod is depressed. With this adjustment the snipping knife will still be responsive to and under the control of the 50 treadle rod 60. The present machine, having its working elements constructed and arranged to control the feed of the material by the co-ordinated movements of the hammer with its retainer finger and the vibrating feed members is substantially automatic 55 in its guiding and feeding forward of the material, so that the edge of the material is guided through the machine with relatively little need of attention on the part 60 of the operator and an accurate folding of the edge to the end of the material without liability of breaking out, is insured. We are aware that the invention may be embodied in other specific forms without de-

parting from the spirit or essential attributes thereof, and we therefore desire the present embodiment to be considered in all respects as illustrative and not restrictive, reference being had to the appended claims 70 rather than to the foregoing description to indicate the scope of the invention.

Having described our invention, what we claim as new and desire to secure by Letters Patent is:

1. A folding machine, comprising feeding mechanism for advancing the material, means mounted to move therewith for turning the edge of the material, and a vibrating hammer for pressing down the turned edge having means co-operative therewith for clamping the material outward therefrom to prevent turning of the material about the hammer.

2. A folding machine, comprising vibrating feeding means for advancing the material, having means mounted to move therewith for turning the edge of the material, a vibrating hammer for pressing down the folded edge timed to clamp the material as it is released by said feeding means, and a retainer member co-operative with said hammer to clamp the material at a distance outward therefrom for the purpose stated.

3. A folding machine, comprising vibrating feeding means for advancing the material, having means mounted to move therewith for turning the material edge, a vibrating hammer for pressing down the edge of the material, and a retainer member carried by said hammer and adapted to clamp the material at a point substantially outward therefrom to prevent turning of the material about the hammer when released by said feeding means.

4. A folding machine, comprising feeding means for advancing the material, having means mounted to move therewith for turning the edge of the material, a vibrating hammer for pressing down the folded edge, and a retainer member yieldingly mounted on said hammer and adapted to clamp the material substantially outward from the hammer as the hammer descends for the purpose stated.

5. A folding machine, comprising feeding means for advancing the material, having means mounted to move therewith for turning the edge of the material, a vibrating hammer for pressing down the folded edge, and a retainer finger mounted on the hammer and extending laterally therefrom, said retainer finger having provision for angular adjustment with respect to the hammer.

6. A folding machine, comprising feeding means for advancing the material, having means co-operative therewith for turning the edge of the material, a vibrating hammer for pressing down the folded edge, and a retainer member yieldingly mounted

- on an arm pivoted to the hammer and equipped with a material clamping finger extending laterally therefrom in the direction from which material is fed, said finger having provision for angular adjustment on said arm.
7. A folding machine, comprising means for feeding sheet material, and a plow abutment mounted to move therewith for turning the edge of the material, said plow abutment having a mounting permitting slight backward yielding thereof for the purpose stated.
8. A folding machine, comprising means for feeding sheet material, and a plow abutment co-operative therewith for turning the edge of the material, said plow abutment having a pivotal mounting equipped with a spring backing permitting said abutment to yield backward slightly in operation for the purpose stated.
9. A folding machine, comprising means for feeding sheet material, and a plow abutment co-operative therewith for turning the edge of the material, said plow abutment having a mounting on said feeding means to be moved therewith, and also movable separately and equipped with a spring backing, whereby a small backward yield thereof is permitted.
10. A folding machine, comprising vibrating feeding means for advancing sheet material, a plow co-operative therewith for turning the edge of the material, said plow having a mounting on an element of said feeding means having separate movement with respect thereto and equipped with a spring backing, and an abutment in position to engage said mounting to cause said plow to be moved backward slightly at each feed movement.
11. A folding machine, comprising means for feeding sheet material step-by-step, and a plow mounted to move therewith for turning the edge of the material, said plow having means associated therewith for imparting relatively small amplitude vibration thereto at each feed movement.
12. A folding machine, comprising means for feeding sheet material, having means mounted to move therewith for turning the edge of the material, a reciprocating hammer for pressing down said turned edge, and an anvil co-operative therewith, said hammer and anvil presenting operative faces sloping upward outwardly whereby the strain on the upper edge of the fold is reduced.
13. A folding machine, comprising means for feeding sheet material step-by-step having means mounted to move therewith for turning the edge of the material, and a reciprocating hammer for pressing down the turned edge having a relatively wide operative face sloping upward outwardly.
14. A folding machine, comprising means for feeding sheet material step-by-step having a plow mounted to move therewith for turning the edge of the material, and a reciprocating hammer for pressing down the turned edge having a relatively wide operative face sloping upward outwardly, and with a lateral extension presenting a diagonal folding edge extending toward and closely adjacent said plow.
15. A folding machine, comprising vibrating feeding means for advancing sheet material step-by-step, having means co-operative therewith for turning the edge of the material, a reciprocating hammer for pressing down the turned edge, and means for operating said hammer to cause the same to have a dwell for clamping the material on the return stroke of said feeding means, consisting in a hammer operating rod, a lever connected to said rod and extending in the same general direction therewith, and means for swinging said lever at each feed movement.
16. A folding machine, comprising feeding means for advancing sheet material having means associated therewith for turning the edge of the material, a hammer for pressing down the turned edge, and means for operating said hammer consisting in a rod pivoted thereto and extending rearwardly therefrom, a lever pivoted to the outer end of said rod and extending generally in parallelism therewith, and operating means for swinging said lever arranged in time to cause said hammer to dwell in clamping engagement with the material on the return stroke of said feeding means and to be lifted during the forward stroke of said feeding means.
17. A machine of the class described having, in combination, means for feeding material comprising elements relatively and progressively adjustable to variably effective and to ineffective positions, means tending to hold the feed means in effective position, means normally opposing the tending means so as to hold the feed means normally in ineffective position, and means for moving the elements to effective positions variably so as to cause them to feed more or less rapidly, at will.
18. A machine of the class described having, in combination, means for feeding material comprising a lower feed block and an upper feed point having a range of relative adjustment from ineffective to effective positions, means tending to hold the feed means in effective positions, means normally opposing the tending means so as to hold the feed means normally in ineffective position, and means for moving the feed block and the feed point to effective positions variably so as to cause them to feed more or less rapidly, at will.
19. A folding machine, comprising fold-

- ing means, vibrating feeding means for advancing the material to the folding means and having operative elements adjustable to operative or inoperative position, manual controlling means for adjusting said elements to the said operative or inoperative position, and a snipping knife connected for power reciprocation and having a mounting connected to be controlled by the same manual controlling means that controls said operative elements of the feeding mechanism, for adjusting said snipping knife to operative or inoperative position at will.
- 15 20. A folding machine, comprising folding means, vibrating feeding elements for advancing the material to the folding means, said elements having a mounting for adjustment to operative or inoperative position, treadle controlled means for rendering said elements operative or inoperative at will, and a power operated reciprocating snipping knife mounted for adjustment from inoperative to operative position, and having connections to be controlled as to such adjustments by said treadle controlled means.
21. A folding machine, comprising folding means, feeding mechanism for advancing the material to the folding means composed of vibrating feeding elements adjustable into operative or inoperative position, spring means for normally holding said elements in inoperative position, a snipping knife connected for power reciprocation and mounted for movement into operative or inoperative position, spring means for normally holding said knife in inoperative position, and a single treadle device for controlling the adjustment of both said feeding elements and said snipping knife.
22. A folding machine, comprising folding means, feeding mechanism for advancing the material to the folding means composed of vibrating feeding elements adjustable into operative or inoperative position, spring means for normally holding said elements in inoperative position, a snipping knife connected for power reciprocation and mounted for movement into operative or inoperative position, spring means for normally holding said knife in inoperative position, and a single treadle device having connections operative by a single continuing movement thereof to first render said feeding elements operative and thereafter to adjust said snipping knife into operative position.
23. A folding machine, comprising feeding mechanism for advancing the material composed of vibrating feeding elements adjustable into operative or inoperative position, spring means tending to hold said elements in full operative position, an adjustable stop to determine the range of action of said spring means whereby the rate of feed may be varied, and a treadle device connected to move said feeding elements to inoperative position on an upward movement thereof and to render said feeding elements operative on a movement thereof in the other direction.
24. A folding machine, comprising folding means, mechanism for feeding material to the folding means composed of vibrating feeding elements adjustable to operative or inoperative position, a power actuated reciprocating snipping knife mounted for adjustment into operative or inoperative position, a single manually controlled means for governing the adjustment of said feeding elements and also the adjustment of said snipping knife for first rendering said feeding elements operative, and by a further movement rendering said snipping knife operative, and means for varying the range of action of said manually controlled means on said feeding elements.
25. A folding machine, comprising vibrating feeding mechanism for advancing the material composed of a lower feed block and an upper feed point, means for adjusting definitely said feed point with respect to said feed block transversely to the line of feed, and means mounted to move with said feeding mechanism for turning the edge of the material.
26. A machine of the class described having, in combination, means for feeding material, and means movable bodily in the line of feed with the material and operating to fold it during such movement.
27. A folding machine having, in combination, a support for a piece of flexible material, means for feeding the material intermittently over the support, and a plow movable with the feeding means operating to fold the material during such movement.
28. A folding machine having, in combination, a hammer, means for feeding material thereto, and means movable with the material towards the hammer and operating to fold the material during such movement.
29. A machine of the class described having, in combination, means for intermittently feeding material, means intermittently moving with the material and folding it during such movement, and means for intermittently retracting the moving means.
30. A folding machine having, in combination, a hammer, a feed block, a feed point, means for intermittently effecting a relative movement of the feed block and the feed point to grip material therebetween and feed it to the hammer, a plow for folding the material, means whereby the margin of the material is gripped between the feed point and the plow, and means whereby the plow moves with the feed point toward the hammer.

31. A folding machine having, in combination, means for feeding material, a plow for folding the material, the plow being pivoted to move in a plane substantially parallel to the plane of feed of the material, and a spring for actuating the plow about its pivot.
32. A folding machine having, in combination, means for feeding material and a spring-controlled plow movable with the feeding means for folding the material.
33. A folding machine having, in combination, a hammer adapted to press a fold in a sheet of material provided with a laterally projecting edge, and means for predetermining the point of fold of the material and for advancing the material to said edge with the material maintained folded at the predetermined point, said edge operating to pinch the material at the predetermined point.
34. A folding machine having, in combination, an anvil, a hammer cooperating therewith having a diagonal folding edge, means for feeding material to the hammer and the anvil, and a plow movable with the feeding means adapted to fold the material at a predetermined point, the feeding means and the plow advancing the material to the diagonal edge so that it may be pinched thereby at the predetermined point, the hammer and the anvil having upwardly, outwardly sloping faces, whereby the strain upon the material is reduced.
35. A machine of the class described having, in combination, folding means, normally ineffective means for feeding material to the folding means, normally ineffective means for snipping the material, and common means for rendering first the feeding means effective and then the snipping means effective.
36. A folding machine having, in combination, a hammer, means for feeding material thereto comprising elements movable into effective and ineffective positions, a continuously operable snipping knife movable into effective and ineffective positions, and common means for moving first the feeding elements into effective position and then the knife into effective position.
37. A folding machine having, in combination, a hammer adapted to press a fold in a sheet of material, vibrating feeding means for advancing material thereto step-by-step, and means for operating the hammer, said operating means being adapted to cause the hammer to dwell during a portion of the return stroke of the feeding means so as to clamp the material on the return stroke of the feeding means, whereby the hammer serves both as a fold-pressing and a clamping means.
38. A folding machine having in combination, a hammer adapted to press a fold in a sheet of material, means for feeding material thereto, and means for imparting a double pinch to the hammer during each cycle of operation of the machine.
39. A folding machine having, in combination, a hammer adapted to press a fold in a sheet of material, means for intermittently feeding material thereto, and means whereby the hammer operates twice upon the material to every operation of the feeding means.
40. A folding machine having, in combination, a hammer adapted to press a fold in a sheet of material having a limiting position, and means for moving the hammer to the limiting position, slightly retracing the movement of the hammer, and again moving the hammer to the limiting position during each cycle of operation of the machine, whereby the hammer is caused to dwell.
41. A folding machine having, in combination, a hammer adapted to press a fold in a sheet of material, and means for operating the hammer comprising means operable to and beyond a dead-center position and to return therefrom, whereby the hammer is caused to dwell.
42. A folding machine having, in combination, a hammer, a vibratory feed point and a vibratory feed block for advancing material thereto, means for operating the feed point, the feed block and the hammer, and means positively connecting the feed point, the feed block and the hammer to the operating means.
43. A folding machine having, in combination, a hammer, means for feeding material thereto and for initiating a fold in the material as it is fed toward the hammer, means for operating the first-named means and the hammer, and means positively connecting the hammer and the first-named means to the operating means.
44. A machine of the class described having, in combination, a feed block, a feed point, an arm constituting a holder therefor, means for vibrating the arm to effect a feeding of the material by the feed point, and means for adjusting the feed point upon the arm transverse to the line of feed to adjust the path of feed movement.
45. A folding machine having, in combination, a feed element, a plow movable therewith, and means for relatively adjusting the feed element and the plow.
46. A folding machine having, in combination, means for feeding material, a hammer, the feeding means being adapted to grip the material when the hammer is ineffective and the hammer being adapted to grip the material when the feeding means is ineffective, and means adapted to clamp the material firmly and to permit the material to

be turned thereabout after the operation of the hammer and before the next succeeding operation of the feeding means.

47. A folding machine having, in combination, a hammer, means for advancing material thereto, and a retainer mounted upon the hammer outwardly thereof for insuring the turning of the material therearound.

48. A folding machine having, in combination, means for feeding material, a hammer, and means positioned outwardly in front of the hammer adapted to clamp the material firmly and about which the material may be turned.

49. A folding machine having, in combination, a hammer, means for feeding material thereto, and a retainer for preventing the material from being pushed outwardly away from the hammer and for determining the point about which the material may be turned in its plane.

50. A folding machine having, in combination, means for intermittently feeding material, means for firmly clamping the material at the end of the feeding movement, a hammer for thereupon pressing a fold in the material, and means for retracting the feeding means and rendering the hammer ineffective, the clamping means being adapted to thereupon lightly clamp the material to permit the material to be turned in its plane prior to the next feeding operation.

51. A folding machine having, in combination, a support for a piece of flexible material, a hammer, means for gripping the material and feeding it over the support to the hammer, means for successively operating the gripping and feeding means and the hammer, a retainer for firmly clamping the material and means whereby the retainer becomes lightly effective before the gripping and feeding means operates to grip the material and after the operation of the hammer, whereby the material is retained in position and may be turned about the retainer before the gripping and feeding means again grips the material.

52. A folding machine having, in combination, a support for a piece of flexible material, a hammer, means for feeding the material over the support to the hammer, a retainer for firmly clamping the material, and means whereby the retainer becomes lightly effective before the operation of the feeding means and after the operation of the hammer.

53. The method of folding flexible material which comprises intermittently feeding the material over a support, clamping the material securely to the support at the end of the feeding operation, pressing a fold in the material while it is so clamped to the support, releasing the pressure upon the fold, and clamping the material lightly to the support to permit turning it about the

clamping point prior to the next feeding operation.

54. A folding machine having, in combination, a hammer adapted to press a fold in a sheet of material, a retainer for clamping the material and means for operating the retainer comprising means operable to and beyond a dead-center position and to return therefrom.

55. A folding machine having, in combination, a hammer, means for advancing material thereto, an arm adjustably mounted on the hammer, and a retainer mounted on the arm.

56. A folding machine having, in combination, a hammer adapted to press a fold in a sheet of material, means for predetermined the point of fold of the material and for advancing the material to the hammer with the material maintained folded at the predetermined point, and means whereby a portion of the hammer first engages the folded sheet at the fold and whereby another portion of the hammer presses out the fold.

57. A folding machine having, in combination, a support for a piece of flexible material, a hammer having a diagonal pinching edge, means for feeding the material intermittently over the support, a plow for intermittently initially folding the material as it is fed, means for moving the plow to the end of said diagonal pinching edge, means whereby said diagonal pinching edge pinches the folded material at the fold adjacent to the plow, and means whereby the hammer subsequently presses out the fold.

58. A folding machine having, in combination, means for feeding material, a plow, and means whereby the edge of the material is adapted to be gripped between the feeding means and the plow.

59. A folding machine having, in combination, a hammer, means for feeding material thereto comprising a feed point, a plow, and means whereby the edge of the material is adapted to be gripped between the side of the feed point and the plow.

60. A folding machine having, in combination, a hammer having a laterally offset edge, means for feeding material to the hammer comprising a feed point, a plow movable with the feeding means adapted to fold the material at a predetermined point, and means whereby the edge of the material is adapted to be gripped between the side of the feed point and the plow, the feeding means and the plow being adapted to advance the material to the laterally offset edge so that it may be pinched thereby at the predetermined point.

61. A machine of the class described having, in combination, means for intermittently feeding material, and means movable

with the material in the line of feed and operating to fold intermittently during such movement.

62. A folding machine having, in combination, a vibratory hammer, means for feeding material thereto, and a plow movable with respect to the hammer for initially folding the material prior to the action thereon of the hammer, the hammer having 5 an operative edge extending close to the plow.

63. A folding machine having, in combination, a hammer having a laterally extending, operative edge, means for feeding 15 material thereto, and a plow movable with the feeding means adapted to fold the material at a predetermined point, the feeding means and the plow being adapted to advance the material to the operative edge so 20 that it may be pinched thereby at the predetermined point.

64. A folding machine having, in combination, a hammer, means for feeding material thereto, and a plow movable with the 25 material and adapted to yield in response to the pressure of the material thereagainst.

65. A folding machine having, in combination, a frame having an abutment member, a hammer, means for feeding material 30 to the hammer, a plow movable with the feeding means having an arm engaging the abutment, and a spring yieldingly maintaining the arm in engagement with the abutment.

66. A folding machine having, in combination, a frame having an abutment member, a hammer, means comprising an intermittently movable feed block for intermittently feeding material to the hammer, a 40 plow pivoted to the feed block having an arm engaging the abutment, and a spring yieldingly maintaining the arm in engagement with the abutment.

67. A folding machine having, in combination, feeding means, a plow, a hammer having an operative edge extending laterally close to the plow, and means for relatively moving the plow and the hammer towards each other.

68. A folding machine having, in combination, means for intermittently feeding material, a plow movable with the feeding means, and means for moving the plow relatively to the feeding means to cause the folding 55 ing of the material.

69. A folding machine having, in combination, a hammer, means for intermittently feeding material thereto, the hammer being adapted to press a fold in the material 60 at each of a plurality of points, and means for imparting a double pinch to the hammer at each of said points between successive operations of the feeding means.

70. A machine of the class described having, in combination, means for folding mate-

rial, means for feeding material to the folding means, means tending to render the feeding means effective, means normally opposing the tending means so as to render the feeding means normally ineffective, 70 means for snipping the material, and common means for controlling the opposing means and the snipping means.

71. A folding machine having, in combination, a hammer having a laterally projecting edge, means for feeding material to 75 said edge, and means for gripping the material as it is fed to predetermine the point of fold of the material, said edge operating to pinch the material at the predetermined point.

72. A folding machine having, in combination, a hammer, means for intermittently feeding material thereto, a plow movable with the feeding means, and means whereby the edge of the material is adapted to be gripped between the feeding means and the plow during the intermittent feed movements.

73. A folding machine having, in combination, a hammer, means for feeding material thereto comprising a feed point, a plow movable with the feeding means, and means for relatively moving the feed point and the plow towards each other to cause 95 the edge of the material to be gripped between them.

74. A folding machine having, in combination, a hammer, means for intermittently feeding material thereto, a plow adapted 100 to initiate a fold in the material during the return movement of the feeding means away from the hammer, and means whereby the feeding means and the plow are moved relatively towards each other during the forward movement of the feeding means towards the hammer to cause the edge of the material to be gripped between the feeding means and the plow during said forward movement.

75. A folding machine having, in combination, a plow having an arm, an abutment engaged by the arm, and means for maintaining the arm yieldingly in engagement with the abutment.

76. A folding machine having, in combination, a hammer, means for feeding material to the hammer, a retainer for clamping the material against movement during pauses in the feed, and a plow movable back and forth in the line of feed.

77. A folding machine having, in combination, means for feeding flexible material, a plow for initiating a fold in the material, and means for actuating the plow in a plane substantially parallel to the plane of the sheet material and at an angle to the direction of feed.

78. A machine of the class described having, in combination, a support for a piece of 180

- flexible material, means for feeding the material intermittently over the support, a folder, means for moving the folder backward along the edge of the material to initiate a fold in the material and forward with the material after it has been folded, and means for actuating the folder to further develop the fold during the forward movement.
- 10 79. A machine of the class described having, in combination, a support for a piece of flexible material, means for feeding the material intermittently over the support, a folder, means for moving the folder with the feed means backward along the edge of the material to form a fold during the pauses in the feed and forward with the material after it has been folded, means for actuating the folder to further develop the 15 fold during the forward movement, and means for pressing the fold thus produced.
80. A folding machine having, in combination, means for feeding flexible material, a folder movable with the feeding 20 means for folding the material, and a fold presser for pressing the folded material having an operative edge extending laterally close to the folder.
81. A folding machine having, in combination, a support for a piece of flexible material, a fold presser, means for feeding the material over the support to the fold presser, and a folder movable with respect to the fold presser for folding the material 25 prior to the action thereon of the fold presser, the fold presser having an operative portion projecting from the edge of the fold presser adjacent to the folder and extending close to a limiting position of movement 30 of the folder.
82. A machine of the class described having, in combination, a support for a piece of flexible material, a fold presser, a folder, and means for moving the folder backward 35 along the edge of the material to form a fold and for moving the folder and the material forward to present the fold to the fold presser, the fold presser having an operative portion projecting from the edge of the fold presser adjacent to the folder and positioned at the limit of forward movement 40 of the folder.
83. A folding machine having, in combination, means for feeding material, a folder for folding the material, a fold presser for pressing the folded material, and means for actuating the folder at an angle to the line of feed towards the fold presser.
84. A folding machine having, in combination, means for feeding material, a folder for folding the material, means for actuating the folder at an angle to the line of feed, and a fold presser for pressing the folded material situated at the end of the path of actuation of the folder.
85. A folding machine having, in combination, a folder for folding material, a fold presser for pressing the folded material, means for actuating the fold presser, and means connected to the actuating means for actuating the folder obliquely towards the fold presser.
86. A folding machine having, in combination, means for feeding material, a folder for initiating a fold in the material, means for actuating the folder in a direction oblique to the line of feed, and a fold presser for pressing the fold initiated by the folder, the fold presser being situated immediately in front of the limiting forward position of the folder in the line of feed.
87. A folding machine having, in combination, a support, means for feeding material over the support, a retainer rearward of the feeding means in the line of feed for holding the material against the support, a folder for initiating a fold in the material, means for actuating the folder in a direction oblique to the line of feed to a position immediately forward of the retainer in the line of feed, and a fold presser for pressing the fold initiated by the folder, the fold presser being situated immediately in front of the limiting forward position of the folder in the line of feed.
88. A folding machine having, in combination, a support, means for feeding material over the support, a knife for slitting the margin of the material, a retainer oppositely disposed to the knife and rearward of the feeding means in the line of feed for holding the material against the support, a folder for initiating a fold in the margin of the material, means for actuating the folder in a direction oblique to the line of feed to a position immediately forward of the retainer in the line of feed, and a fold presser for pressing the fold initiated by the plow, the fold presser being situated immediately in front of the limiting position of the folder in the line of feed.

In testimony whereof, we have signed our names to this specification.

CHARLES BROSTROM.
ANDREW R. RIDDERSTROM.

Certificate of Correction.

It is hereby certified that in Letters Patent No. 1,527,394, granted February 24, 1925, upon the application of Charles G. Brostrom, of Lynn, and Andrew R. Ridderstrom, of Nahant, Massachusetts, for an improvement in "Folding Machines," errors appear in the printed specification requiring correction as follows: Page 2, line 85, for the numeral "8" read 18; page 6, line 74, for the word "fed" read *feed*; page 7, line 29, strike out the words "*m* whose edges E is to folded is" and insert instead, *As already explained the blows of*; and that the said Letters Patent should be read with these corrections therein that the same may conform to the record of the case in the Patent Office.

Signed and sealed this 12th day of May, A. D. 1925.

[SEAL.]

KARL FENNING,
Acting Commissioner of Patents
